CLAIM

The ornamental design for a lockout device, as shown and described.

DESCRIPTION

FIG. 1 is a top, front, and right side perspective view of a lockout device;

FIG. 2 is a bottom, rear, and right side perspective view of the lockout device of FIG. 1;

FIG. 3 is a front elevational view of the lockout device of FIG. 1;

FIG. 4 is a rear elevational view of the lockout device of FIG. 1;

FIG. 5 is a left side elevational view of the lockout device of FIG. 1;

FIG. 6 is a right side elevational view of the lockout device of FIG. 1;

FIG. 7 is a top plan view of the lockout device of FIG. 1; and,

FIG. 8 is a bottom plan view of the lockout device of FIG. 1.

The broken lines illustrate portions of the lockout device that form no part of the claimed invention.

1 Claim, 6 Drawing Sheets
